ALPHABETIC PRINTING MECHANISM

Horace S. Beattie, East Orange, N. J., assignor to International Business Machines Corporation, New York, N. Y., a corporation of New York

Application February 19, 1943, Serial No. 476,419

9 Claims. (Cl. 101—93)

This invention relates to alphabet printing mechanism and more particularly to the type controlled by perforated records.

The main object of the invention is to provide means to increase the character printing capacity of the machine without requiring the use of additional pilot holes beyond those now available in a record column.

By way of explanation it is well known that alphabetic printing characters are divided into groups, usually three, selected by 0, X and R pilot holes. Ordinarily printing from numerals is also required and these are selected by perforations at the numeral index point positions alone and without the use of a pilot hole.

The 0, X, R positions are at the top of card and occupy such space that additional space for more pilot holes is not available in a standard size card.

The main object of the present invention is attained by providing for the selection of additional alphabetic printing characters, punctuation, special symbols, etc., by perforating successive index points, i. e. at 1—0, 2—1, etc., 9—8. The sensing of such holes will select a character different from one which would be selected by a single hole alone.

While the above novel principle of the invention is utilized for selection of type as just described it is preferable to provide for the selection of additional groups of type by the pilot holes as well. Hence, while the novel selecting mechanism provides for the selection of a type in a selected group by two holes, the pilot holes are provided to select the desired group of a plurality of groups of type.

The advantage arising from the invention is that alphabetic characters can be duplicated providing one series as capital letters and the other series as lower case. This extended capacity enables printing of reports corresponding to typing from a conventional typewriter making reports printed by a record controlled alphabet tabulating machine more attractive.

The code adopted for selection of perforations is one that can be used with a conventional card perforating machine, thus avoiding any special perforating instrumentalities and enabling perforation of holes in the card in the customary manner.

Other objects of the invention will be pointed out in the following description and claims and illustrated in the accompanying drawings, which disclose, by way of example, the principle of the

invention and the best mode, which has been contemplated, of applying that principle.

In said drawings:

Fig. 1 is a diagram showing the particular numerals, capitals of the alphabet, lower case alphabet, special symbol type which are selected under control of the perforations 1—9 singly or in combination 9—8, 8—7, 7—6, 6—5, etc., and in combination with the special R, X, and 0 perforations.

Fig. 2 is a sectional view showing diagrammatically the card feeding mechanism which may be utilized as a control for the improved printing mechanism.

Fig. 3 is a sectional view showing the main operating parts of the printing mechanism for selecting the numerical and alphabetical characters, depending upon the perforations made in the card column analyzed.

Fig. 4 is a timing diagram of the machine.

Fig. 5 is a view in elevation showing particularly the arrangement of the operating shafts and the driving cams and their associated follower members.

Fig. 6 is a sectional view showing the formation of the main operating cams of the machine and the associated driving trains.

Fig. 7 is a wiring diagram showing the plug connections and circuit arrangement.

Fig. 8 is a view in side elevation showing one of the operating trains.

Fig. 9 is a view in side elevation showing another operating train.

Card feed and machine drive

The machine in which the present improvements have been incorporated is well known and is disclosed in the patents to Lake No. 1,379,268, dated May 24, 1921, Lake No. 1,600,413, dated September 21, 1926, and the patent to Daly et al. No. 1,896,540, dated February 7, 1933.

In machines illustrated in detail in the above described patents and generally herein, tabulating cards 10 (Fig. 2) are adapted to be fed singly by a picker 11 from a supply stack to a pair of upper feeding rollers 12 which convey the card so as to have the perforations of the card analyzed by the usual perforation analyzing brushes 13 while the card is in motion. The card analyzed then passes to a lower set of feeding rollers 14 which then convey the card to a storage hopper, usual in the type of machine referred to.

Card feeding operations are instituted by the usual manual start key designated as ST in the

last mentioned patent so as to cause by an electrical circuit the energization of a card feed clutch magnet 15.

The power for driving the card feeding rollers and other parts of the machine is derived from a motor (not shown) which by a belt 16 and pulley 17 constantly rotates a ratchet wheel 18 secured thereto. The pulley 17 and ratchet wheel 18 are loosely mounted upon a shaft 18.

In Fig. 2 there is shown the card feed clutch for causing card feed and is similar to the card feed clutch disclosed in Fig. 1a of the Lake Patent No. 1,822,594, dated September 8, 1931, to which reference should be had for details of construction and operation.

Upon completion of the electrical circuit to clutch magnet 15, the latter attracts its armature 20 to raise a clutch lever 21 to thereby unlatch the latter from a clutch pawl 22. The latter is then drawn by a related spring 23 to engage the constantly rotating ratchet wheel 18. The clutch pawl 22 is carried by a bar 25, which is secured to a disk 26 secured to shaft 18 and to the latter there is secured a pinion 27.

The construction and operation of the card feed clutch, as is well known, are such that upon energization of magnet 15, disk 26 will be rotated and successive rotations of the shaft 18, and therefore pinion 27, will ensue as long as tabulating operations are desired.

The pinion 27 is in mesh with a gear 28 and the latter drives the upper set of feeding rollers 12 and the lower set of feeding rollers 14. The upper set of feeding rollers is intergeared by pinions 29, one of which is rotatable with a gear 30 in mesh with the driving gear 28. The latter also meshes with a pinion 31 which is rotatable with one of a pair of intergeared pinions 32 carried by the rollers 14 which drive the lower set of feeding rollers 14. The driving gear 28 is of sufficient width to drive a gear 34 so that by a train of gears 35, 36 a main drive shaft 37 is driven. (See Fig. 9.) It is understood that as is usual in tabulating machines the card feed clutch is so designed and the gears are so proportioned that shaft 37 will be given a complete revolution in the arrow direction shown in Fig. 2.

It is customary in the type of machine described to cause printing from numeral type of a printing mechanism which are presented to a printing line and which are selected in accordance with the analyzing of the perforations of the card, and to carry out the numeral printing function in a novel manner the improved construction will now be described.

Digit or numeral printing mechanism

The printing mechanism constructed as shown herein may consist of a plurality of orders, the number being dependent upon the number of numerical or alphabetical characters which are to be printed. Fig. 3 shows a plurality of control magnets for four orders but the type selecting mechanism for one order and it is to be understood that the type selecting mechanism is duplicated for as many orders as is required.

The printing elements preferably consist of one or more printing wheels 40, each of which is centrally apertured so as to overlie a flange or hub 41. The hub 41 is integral with an arm 42 pivoted upon a rod 43 and the rocking of such arm will carry the selected printing type of the printing wheel 40 against a conventional platen 44, it being understood that interposed between the print-

ing wheels 40 and the paper strip surrounding the platen 44 there is a conventional inking ribbon. Each of the arms 42 is provided with an extension 45 guided in a slotted bar 46 and in a hole in the slotted bar 46 there is interposed a spring 47 which, when released for action, rocks the arm 42 to impress the printing wheel 40 against the platen 44. The spring 47 is normally restrained against action by means of a latch pawl 48 which normally latches the arm 42. To further suitably guide the arms 42 and space the printing wheels it will be noted that each is provided with a depending projection 49 fitting in a respective slot 50 of a guide block 51.

Reference character 52 designates a print controlling ball which is pivotally mounted by arms 123 on the rod 43 (see also Fig. 6) with the cross bar within the flanges 41 and as will be subsequently described the printing controlling ball 52 is reciprocated four different times during the operation of the machine when printing from the unlatched printing wheels is to be effected. The ball 52 rocks counterclockwise or downwardly to the right from the position shown in Fig. 3 to enable unrestrained movement of the printing wheels 40 to printing position when desired and after the printing impression has been effected the ball 52 is restored by means to be subsequently described so that by coaction with the flanges 41 the arms 42 and the printing wheels 40 mounted thereon will be restored and relatched. During such restoration the extension 45 is relatched by the latch arm 48. It is to be understood, of course, that while the printing wheels 40 are to be mounted closely together they are to be suitably spaced for enabling free independent rotation of the series of printing wheels 40.

Each printing wheel 40 is provided with a group of numeral printing characters for printing the numerals 0 to 9, a complete set of alphabetic characters for printing capitals thereof and a complete set of lower case alphabetic characters. At this time there will now be explained the manner in which numeral printing is effected under control of the card perforations 0 to 9, inclusive.

In Fig. 3 it will be observed that for the selection of the numeral printing characters 1 to 9 a variable rotation of the printing wheel 40 in a counterclockwise direction is necessary, it being observed that to select the numeral type "1" the least counterclockwise rotation of the printing wheel 40 is necessary whereas for selection of the numeral type 9 a greater extent of rotation of the printing wheel 40 in the same direction is necessary. A clutch controlled type selecting mechanism is provided for effecting this variable rotation under control of the 1-9 card perforations.

From Fig. 3 it will be observed that the numeral printing characters 1-9 are provided on alternate gear teeth of the printing wheel 40 and said gear teeth mesh with the teeth of a clutch gear 53, there being, of course, one clutch gear for each printing wheel 40. The main drive shaft 37 drives through an intermeshing gear 55 (Fig. 9), a shaft carrying tube 57 and which tube is provided on its periphery with ratchet shaped clutch teeth 58, these teeth being coextensive with the length of the tube 57. The clutch teeth 58 are arranged in three groups of eighteen each and through the intermediate gear driving connection 55 with shaft 37 the tube 57 is given one and one-third revolutions for each cycle of operation of the machine. The clutch gears 53 are mounted

upon the tube 57 and are suitably spaced the same width as the printing wheels 48 so that each clutch gear 53 will mesh with the related printing wheel 48 that it drives.

Each clutch gear 53 has pivotally mounted thereon a clutch pawl 59 provided with a clutch tooth 58. A spring 61 secured to the clutch pawl 59 normally urges the clutch pawl 59 so that the clutch tooth 58 will engage one of the ratchet teeth 58 but such action is normally restrained by a clutch release arm 62, the arm having a projection 63 which normally engages an extension 64 of the clutch pawl 59.

As is well known in the operation of the clutch mechanism now being described, at the moment the clutch release arm 62 is rocked the clutch pawl 59 will be free to engage one of the clutch notches 58 and since the tube 57 is driven in a clockwise direction the clutch gear 53 will be driven in the same direction so as to rotate the printing wheel 48 counterclockwise. The clutch engagement of the clutch pawl 59 and the engaged notch 58 is maintained until the extension 64 of the clutch pawl 59 again strikes the extension 63 of clutch release arm 62 which, in the meantime, has returned to the normal position shown in Fig. 3. This will disengage the clutch pawl 59 from the clutch tooth 58 it engaged. It will be observed that in the normal position of the clutch pawl 59, this position is also maintained by a detent block 65 which is integral with the clutch gear 53.

The clutch teeth 58 are arranged in three similar groups and one of the teeth designated 1, 2, 3 . . . 9 of the group which is effective is engaged by the clutch pawl 59 to effect the desired extent of rotation of the printing wheel to select the printing characters 1 to 9, dependent upon which tooth is engaged. The manner in which the desired clutch engagement with the required clutch tooth 58 is effected under control of the card perforations will now be described with particular reference to Fig. 3.

Reference numeral 70 designates a reciprocating shaft which is rotated counterclockwise 180° and is then reversely rotated. Attached to the shaft 70 is a clutch disk 71 provided with clutch teeth 72 designated 1-9 and 0. During the counterclockwise rotation of the clutch disk 71, the clutch teeth 72 pass by the clutch engaging portion 73 of a clutch pawl 74 and a clutch tooth will be engaged according to the corresponding perforation analyzed.

The card is perforated with holes to represent the digits 0-9, as is customary, and is passed by the analyzing brushes 13 to analyze the index points in the order 9,8,7 . . . 0. When the analyzing brush 13 senses a hole, a circuit is closed to a printing control magnet 75 (Figs. 2 and 3) by a circuit to be later described and for each card column analyzed there is a printing control magnet 75. When a printing control magnet 75 is energized, its armature 76 is attracted so as to pull a call link 77 upwardly. Each call link 77 is pivotally connected to one arm of an irregularly shaped member which in general comprises a clutch release arm 78 which has a latch extension 79 normally engaging an extension 80 of the clutch pawl 74. The clutch pawl 74 is pivoted by a stud 81 to an operating disk 82. When an analyzing brush 13 encounters a card perforation a related magnet 75 will be energized and as a result clutch pawl 74 will engage one of the teeth 72 dependent upon which perforation is encountered, so that during the counterclockwise

rotation of the shaft 70 the operating disk 82 will be given an extent of movement which is dependent upon the perforation analyzed, the disk being given greatest extent of movement when the 9 perforation is in the column and the least extent of movement when the 1 perforation is analyzed, as is evident in Fig. 3.

The means for rocking the shaft 70 is best shown in Fig. 6, wherein it will be noted that secured to the main drive shaft 37 is an eccentric cam 83 and cooperating with the cam 83 is a follower arm 84 which is an integral part of a segment 85 meshing with a gear 86 secured to the rock shaft 70. The formation of the cam 83 is such that as the card perforations pass the analyzing brush 13 the segment 85 will rock shaft 70 to cause the correspondingly designated ratchet teeth 72 to pass by the clutch pawl 74, as is evident from the timing diagram of Fig. 4.

20 The clutch disk 71 is therefore, rotated at a constant speed from the beginning of a machine cycle to 184°, then accelerates in speed, and thereafter to a constant speed to 269°. (See Fig. 4.) After 269° shaft 70 and clutch disk 71 are rotated in a reverse or clockwise direction. In so doing a projecting cam portion 87 of the clutch disk 71 bearing against the extension 78 of the clutch pawl 74 causes operating disk 82 to be restored clockwise. The cam 83 (Fig. 6) is provided with a cam surface which will cause the clutch disk 71 to be rocked counterclockwise slightly beyond the position shown in Fig. 3 in order that the clutch pawl 74 is relatched by the clutch release arm 78. After such relatching clutch disk 71 comes back to the normal position shown in Fig. 3.

The variable extent of counterclockwise rotation of the operating disk 82 is provided to determine the time of engagement of the clutch pawl 59 with the clutch tube 57 in the following manner: The operating disk 82 carries guide pins 88 receiving guide slots 89 of an arcuate plate 90. A latch pawl 91 latches the plate 90 in the position shown in Fig. 3 against the action of a spring 92 connected to the plate 90 and which spring is also the operating spring for the clutch pawl 74. The plate 90 is provided with a cam projection 93 in the plane of an extension 94 of the clutch release arm 62. The operating disk 82 is rotated counterclockwise after it is picked up by the clutch engagement so that projection 93 coacting with the extension 94 will rock the clutch release arm 62 to cause pawl 59 to engage one of the teeth 58 which corresponds in numeral designations to the numeral designation of the perforation analyzed.

Before the time that the variable rotation of the operating disk 82 is determined under control of the card perforations and effected, the clutch tube 57 has been rotated to some extent and as the clutch teeth 58 of the group that is effective pass by the clutch pawl 59, the clutch release arm 62 may be rocked by the cam extension 93 of the plate 90 and dependent upon the time of the rocking of the clutch release arm 62 a variable extent of rotation of the gear 53 will be given until the termination of the machine cycle. However, at this time, the type carrier wheel 40 has not been rotated counterclockwise sufficiently so that the selected numeral type is coordinated with the platen 44. However, during the next machine cycle the rotation of the clutch tube 57 will effect a further clockwise rotation of the gear 53 effecting a supplemental counterclockwise rotation of the printing wheel 40 until the selected

numeral type is at the printing position. When gear 53 is rotated sufficiently so that the extension 58 of the clutch release arm 52 engages the clutch pawl 59 the latter will be rocked out of engagement with the teeth 58 it previously engaged to cause the clutch mechanism to be in the disengaged position shown in Fig. 3. Printing from the selected numeral type is effected at 111½° of the machine cycle subsequent to the machine cycle the card was analyzed and is effected by mechanism which will now be described.

Reference numeral 100 represents a zone selecting disk which determines by its variable extent of counterclockwise rotation from which group of type characters the type selected by the 1-9 holes is to be printed from. The variable extent of rotation of the zone selector disk 100 is determined after the digit representing perforations 1-9 are analyzed and is determined by the presence of the perforations O, X and R in their customary index point positions. In the absence of such special perforations the card column will represent the digits 1-9 and accordingly means is provided to effect the variable displacement of the zone selector disk 100 when printing of the digits 1-9 is to be effected.

For driving the zone selector disk 100 counterclockwise there is provided a reciprocating shaft 101 and this shaft is reciprocated by a driving train now to be described. Secured to shaft 37 is a profile cam 102 (Fig. 8) and cooperating with this cam is a bell-crank shaped follower member 103 and to this member there is connected a link 104 (see also Fig. 6) pivoted to an arm secured to the reciprocating shaft 101. The formation of the cam 102 is such that between 88° and 165° of the machine cycle the shaft 101 is restored in a clockwise direction after having been rotated counterclockwise so that at about 165° of the machine cycle, as shown in the timing diagram, the cam 102 will be in position so that thereafter O, X, R, N, clutch notches 105 (Fig. 3) formed in a disk 108 secured to rack shaft 101 will be passed in succession by the clutch engaging end 106 of a normally latched clutch pawl 107 which is pivoted on the zone selector disk 100. Of course, in the absence of the special perforations O, X, and R there will be no engagement of the pawl 107 with such designated notches but in printing numerals the notch N will be engaged by the clutch pawl 107. To effect this it will be noted that the disk 82 is provided with a cam portion 82a which, after its counterclockwise rotation has been initiated, will engage an interposer pawl 109 pivoted to an extending arm of the clutch release arm 78 and with the interposer 109 elevated it will be noted that it is now in operative relationship with an extension 110 of a clutch release arm 111 cooperating with the clutch pawl 107 in the customary manner. At 225° of the machine cycle the notch N of the clutch disk 108 will be in cooperation with the clutch pawl 107 and at this time by means to be subsequently described magnet 75 is energized and the clutch release arm 78 will be rocked so that the interposer 109 will be shifted to the right and by its cooperation with the extension 110 of the clutch release arm 111 will rock the same counterclockwise to unlatch the clutch pawl 107. By such release the engaging portion 106 will engage the notch N and the zone selecting disk 100 will be driven counterclockwise. The counterclockwise rotation given to the zone selector disk 100 is sufficient for a cam projection 112 thereof to engage at 88° of the next machine cycle a

projection 113 which is an extension of the latch member 48, thereby rocking the latch member 48. While the latch member 48 is retained in its unlatched position, and after 88° of the next machine cycle the bail 52 is rocked downwardly releasing arm 42 for movement to permit printing from the selected numeral characters and printing is effected under control of the bail 52 so as to occur at 111.5° of the machine cycle as shown by the designation "N-Prints" in the timing diagram. After the cam projection 112 has engaged the latch member 48 to permit printing under control of bail 52 the shaft 101 is restored in a clockwise direction as previously stated and during the clockwise rotation of the disk 108 a projection 114 thereof will engage the clutch portion 106 of the clutch pawl 107 to drive disk 100 clockwise and slightly beyond normal position to cause the clutch pawl to be relatched by the clutch release arm 111 after which the clutch disk 108 is given a counterclockwise rotation so as to come to normal position. The operating train for enabling bail 52 to print from the selected digit will now be described:

Reference has been made to bail 52 and the latter is reciprocated several times during the operation of the machine when printing operations are to be effected.

From Fig. 6 it will be seen that shaft 37 drives a cam 115 which cooperates with a follower bell crank 116 which is connected by a link 117 to a double arm 118. Arm 118 is connected by links 121 and 122 to one arm 123 of a pair of arms which carry bail 52. Link 121 is also carried by an arm 119 which has a pivot connection 120 to link 121. The cam formation of cam 115 is such as to rock bail 52 to the right and then to the left four times. As arm 118 is initially rocked clockwise under control of cam 115, arm 119 restrains link 121 so that as the left end of link 121 moves downwardly and to the right the right end moves upwardly and also to the right and through the interconnecting link 122 bail 52 will be rocked to the right to enable printing. At one rocked position of arm 118, its pivot connection to link 121, pivot 124, and the pivot connection of link 122 to arm 123 are all in a straight line. Thereafter further clockwise rocking of arm 118 will cause pivot 124 to pass above the mid-center position to break the toggle and thus move bail 52 clockwise to restored position. When arm 118 is restored counterclockwise the reverse action takes place. From the timing diagram it will be seen that at about 88° of the machine cycle, at which time member 48 has been rocked to unlatch extension 45, the bail 52 begins to rock counterclockwise and printing wheel 40 will roll slightly over gear 53 and during this rolling action the selected type will be brought to such a position as to strike the platen 44 and print this digit. The restoration of bail 52 will relatch the printing wheels 40 in normal position.

The means for transmitting the impulse to the printing control magnet 75 at the time the notch N is to be engaged by the clutch pawl 107 will now be described: From Fig. 2 it will be seen that for each card column the related brush is wired to a plug socket 125 and a plug connection may be made from this socket to either a plug socket 126 or a plug socket 127 (see Fig. 7), depending whether numeral printing is to be effected for that card column, or alphabetic and numeral printing. This brings into circuit connection with the printing control magnet 75 (see Fig. 7)

either cam operated contacts 128 or 129, cam contacts 128 being closed by a cam driven by a shaft 37 so as to close during only the index points 1-9. When the plug connection is made to plug socket 127 the analyzing brush 13 will be connected in the circuit with the printing control magnet 75 through contacts 129 which are closed by a cam driven by shaft 37 so as to close during all of the index point positions, that is, 1-9, 0, X and R.

Referring to Fig. 3, pivoted at 130 is a bell crank shaped arm 131 urged by a spring 132 so that it bears against a cam portion 134 of the clutch disk 82 and also so that another arm thereof engages the center blade of a contact assembly which comprises normally closed contacts 135 and normally open contacts 136. When the disk 82 is rotated counterclockwise, which is effected when any of the numeral positions 1-9 are analyzed, the bell crank arm 131 will be rocked because one arm drops from the high cam portion 134 to a lower portion so that the other arm of the bell crank will enable contacts 135 to open and contacts 136 to close. For each column in which numeral printing is to be effected there is provided a plug socket 137 and where printing is to be effected in three orders, as shown in Fig. 7, they are interconnected by plug connections 138. By means of a plug connection 139 one or more orders selected for numerical printing may be connected to cam operated contacts 140 which are adapted to close at 225° in the machine cycle. This impulse then extends through the particular contacts 136 which are closed, thence through cam contacts 141 which are closed by a cam driven by shaft 37 so as to close such contacts between 225-234°, the circuit then being extended through the printing control magnet 75 to the other side of the line. Therefore, at 225° an impulse is transmitted to the printing control magnet 75 so as to cause the rotation of the related zone selector disk 100 (Fig. 3) in a counterclockwise direction to thereby enable printing from the selected numeral type. While the circuit has been described in connection with a single column, it will be obvious that the same operation is performed for other card columns. However, up to the present description no consideration has been given to the suppression of printing of zeros at the left of the digit in the highest denominational order, or for printing of zeros at the right of the first significant digit so as to fill in the necessary zeros. The preferred form of arrangement for securing this result will now be described in detail:

When the card columns are plugged up to effect numeral printing it is necessary, of course, that zeros in the lower denominational orders be printed, such as, for example in the number "400." Due to the fact that the cam operated contacts 128 are closed only during the time the 1-9 perforations are analyzed, provision is made for causing the release of the printing wheels 40 of lower orders under control of the printing selecting mechanism of a higher order when that order is utilized to print a significant digit. The necessity of such zero printing is well known in the printing art and the preferred arrangement will now be described in detail. A pitman 160 is reciprocated by a cam 161 (Fig. 8) driven by shaft 31 and said pitman is connected to an arm 162 which is secured to a shaft 151, shown in both Figures 3 and 8. The shaft 151 at the portion which is coextensive with the series of interposers 109 (Fig. 3) is a "half shaft" and the interposers 109 normally overlie the flattened por-

tion of the rock shaft 151. The downward movement of the pitman 160 under control of cam 161 will rock shaft 151 clockwise and from the timing diagram (Fig. 4) it will be observed that this rocking of the shaft is effected between 198° and 216° of the machine cycle, and after 216° of the machine cycle the shaft 151 is maintained in its rocked position until about 252° of the machine cycle so that at 225° of the machine cycle which is the impulse time for the print control magnets 75 the interposers 109 will be positioned in cooperative relationship with the extensions 110 of the clutch release arm 111.

With particular reference to Fig. 7 it will be noted that for numerical printing plug connections 152 are made between related pairs of plug sockets 154. Considering now printing of digits in the highest order it will be observed that the impulse directed to the printing magnet 75 of such order is also extended by a wire 155 and by means of the plug connection 152 the impulse is directed through the contacts 135 of the next lower denominational order which are normally closed, thence through cam contacts 141 which are closed at the time this impulse is directed, thence through the printing control magnet of the next lower or tens denominational order. This impulse directed to the printing control magnet of the tens order will, in the manner previously described, cause the unlatching of the printing wheel 40 of the tens order but in view of the fact that the printing wheel 40 has not been differentially rotated because it was not utilized to print any of the digits 1-9 inclusive, the printing wheel is in the position shown in Fig. 3. The movement of the print bail 52 will enable such printing wheel to rotate over the now stationary gear 53 and in such rolling operation the "0" printing character will strike the platen 44, thus printing a 0 in this order.

Obviously, if the next lower, or the units order, is not utilized to print any of the significant digits 1-9, the impulse transmitted to the print control magnet for the tens order will also be directed by means of a plug connection 152 through the normally closed contacts 135 for the units order, thence through the cam operated contacts 141 to the printing control magnet 75 for the units order, thus effecting printing of zeros in this order. However, if the units order was utilized for printing a significant digit the contacts 135 associated with the units order would be open so that the impulse could not be transmitted from the tens order to the units order to effect zero printing and instead printing of the selected digit 1-9 will be effected.

It is to be understood that printing of zeros for orders above the first significant digit will be automatically suppressed. For example, if the units order was selected to print only a significant digit 1-9 and even though the tens and hundreds order columns were perforated to represent "0," as is customary to fill out the higher order columns with zeros to show that all card columns have been punched, these zeros will be ineffective for control purposes by reason of the fact that contacts 128 are not closed during the time the zero perforations are analyzed. Hence, the printing wheels 40 of the orders above the order utilized to print the first significant digit will remain in normally latched position shown in Fig. 3 and no printing will be effected for such higher orders. Hence, zero printing for higher denominational orders is automatically suppressed.

For the purpose of positively withdrawing the

armature 76 from the magnets there is provided a knockoff ball 66 (Fig. 3) which is pivoted upon a rock shaft 67. A dentated cam 68 (Fig. 9) secured to the main drive shaft 37 cooperates with a follower pitman 69 which is connected to an arm secured to the rock shaft 67. The dentations of the cam 68 are of such formation that after each time a printing magnet 75 has been energized and its armature 76 attracted, the ball 66 will be depressed and by its cooperation with the clutch release arm 78 the call link 77 will be moved downwardly and the armature 76 positively moved away from the cores of the magnets, thereby overcoming the effect of residual magnetism which might cause the armature 76 to be continuously attracted by the magnet 75.

Alphabetic printing mechanism—Printing of capital letters

In addition to printing of the numerals the present machine is provided with an alphabetic printing mechanism which is capable of printing not only alphabetic capital letters but also alphabetic characters in lower case. At this time there will be described the performance of the machine in printing the alphabetic capital letters.

As previously described, when the machine is to perform in this manner plug connections are made between the analyzing brush sockets 125 and the plug sockets 127 so that impulses will be directed to the print control magnets of the different orders under control of the perforation 1-9 and also the type group selecting perforations R, X and 0 in the same column. The operation of the machine will be described in connection with a specific example, namely the printing of the alphabet capital letter W which, from Fig. 1, it will be noted, is selected for printing by a perforation at the "6" index point position and also a supplementary perforation at the "0" index point position. The card passes by the analyzing brushes 13 in the order 9, 8, 7, etc., and when the 6 perforation is encountered at substantially 63° of the timing diagram (Fig. 4) an impulse is transmitted to the related printing control magnet 75 and by the time that the effect of this impulse causes the release of clutch pawl 74 the "6" notch 72 of the disk 71 is correlated with the clutch pawl 74 and by the release of the pawl 74 this notch is engaged at 76° in the machine cycle. Further rotation of the drive shaft 70 will then drive the operating disk 82 counterclockwise for the purpose of operating the clutch release arm 62 as previously described. The initial rotation of the operating disk 82 causes, by its cam formation 82a, the rocking of the interposer 109 so as to be moved in operative relationship with the extension 110 of the clutch release arm 111 preparatory to the second energization of magnet 75.

From the timing diagram it will be observed that at about 171° of the machine cycle the 0 perforation is analyzed and at this time the "0" notch 105 of the clutch disk 108 is in operative relationship with the clutch pawl 107. The supplemental impulse directed to the printing control magnet 75 will, in a manner previously described, release this clutch pawl so as to engage the "0" notch 105 and the zone selector disk 100 now begins to rotate counterclockwise from this point in the machine operation. During the rotation of the zone selector disk 100 the disk 82 is also being rotated counterclockwise and at about 227½° of the machine cycle the cam projection

83 engages the projection 84 of the clutch release arm 62 and at this time the clutch release arm 62 will be rocked to unlatch the clutch pawl 69 which at this time is in operative relationship with the "6" notch 58 of the effective series. It is to be understood that from the beginning of the machine cycle the clutch tube 57 has been rotating counterclockwise in synchronism with the rotation of the disks 82 and 100 to effect this operative relationship. The timing of the engagement of the "6" notch 58 of the clutch tube 57 is shown in Fig. 4 to occur at 227½° and after this point in the machine cycle the gear 53 continues to rotate counterclockwise so that the rotation of the gear 53 in this direction will rotate the printing wheel 40 in a counterclockwise direction.

In the rotation of disk 100 cam portion 112 ultimately strikes the projection 113 to rock the latch arm 48 and from the timing diagram it will be observed that this occurs at 249½° of the machine cycle. At this time the bail 52 is beginning to rock counterclockwise downwardly to the right as viewed in Fig. 3 and since the arm 42 of the order now being considered has been unlatched, printing wheel 40 will roll over the gear 53 at the same time that the gear 53 is driving the printing wheel 40 counterclockwise. The print bail 52 has been moved at 269° of the machine cycle sufficiently far so that the print wheel 40 will strike the platen 44 and from the timing diagram it will be observed that at 269° of the machine cycle the printing wheel has been rotated counterclockwise eleven steps from the time of engagement at 227½°, thereby bringing the printing character W to the printing position so that this printing character will strike the printing platen 44 and effect the impression of this letter. Eleven teeth of printing wheel 40 from 0 selects the type W. Of course, after this operation the bail 40 relatches the printing wheel 42 in the normal position.

It will be understood that for the selection of any of the capital letters in the group selected by the "0" perforation, which capital letters according to Fig. 1 are S-Z, inclusive, the clutch causing the driving of the printing wheel 40 will be picked up at different times. For printing the capital letter Z the printing wheel 40 will be rotated a greater extent than for the selection of the printing character W, whereas for selection of the letter S a lesser rotation of the printing wheel 40 will be effected, this being determined by the perforations 2-9, inclusive.

As for the time of printing the capital letters determined by the presence of the "0" perforation, it will be observed from the timing diagram that this occurs in the same machine cycle that the card is analyzed in contradistinction to the machine operation for printing the numerals, it being recalled that this is effected during the next machine cycle. In all cases printing from the selected characters of the group S-Z also occurs at 269° of the machine cycle irrespective of the S-Z type selected. For the selection of a desired type it is only necessary to effect the desired rotation of the print wheel 40 to bring it to printing position and this is determined by the presence of the digit perforations 2-9 in the card column selected for control.

There will now be described the performance of the machine in the selection of the capital letters when the controlling card column has a perforation at the "X" index point position. This will be described in connection with an ex-

ample, namely the selection of the capital letter "O" and this is selected by perforations at the "6" index point position and also at the "X" index point position.

The manner of effecting the clutch connection for initiating the rotation of the printing wheel 40 is the same as has been described in connection with the selection of the "W" printing character and the clutch engagement is effected at 227 $\frac{3}{4}$ ° of the printing cycle. However, since there is no perforation at the "0" index point position, the printing wheel 40 will not be unlatched for a printing operation at 269° and therefore, with clutch pawl 59 maintained in engaged position with respect to the clutch tube 51 the gear 53 will continue to rotate and, therefore, continue the counterclockwise rotation of the printing wheel 40 so that during this maintained rotation of the printing wheel the group of printing characters J-R will be brought into operative correlation with the platen 44. When the perforation at the X index point position is analyzed, the clutch pawl 107 is released and the zone selector disk 100 will, therefore, be driven counterclockwise and while the printing wheel 40 is still rotating the latch arm 48 is moved to unlatching position by means of the projection 112 of the zone selector disk 100 and from the timing diagram it will be observed that by the sensing of the perforation at the X index point position at 189° the latch arm 48 will be rocked to unlatching position at 313° of the same machine cycle that the card is analyzed. The bail 52 begins to move counterclockwise at this point in the machine cycle so that at 336 $\frac{1}{2}$ ° of the machine cycle printing is effected from the printing wheel which has rotated to an extent of 29 teeth from normal to select the printing character and in the present example printing will be effected to print the capital letter "O."

With this understanding of the operation of the machine it will be evident that if the zone selecting perforation was at the "R" index point position the further continued rotation of the driving gear 53 will correlate the group of printing characters A-I with the printing platen, the particular character of this group which is to be selected depending upon the index point analyzed and the time of engagement of the clutch for driving the disk 82. Under control of the R zone selecting perforation the zone selector disk 100 will be clutched for counterclockwise rotation at 207° of the machine cycle and from the timing diagram it will be observed that the arm 48 is unlatched at 22 $\frac{1}{2}$ ° of the machine cycle subsequent to that in which the card is analyzed. At this point in the machine cycle the bail 52 is given its counterclockwise rotation so as to effect printing from the selected printing character at 44° of the machine cycle subsequent to that in which the card is analyzed.

It will be observed that as far as the performance of the machine for printing capital letters is concerned the different groups are selected by the presence of the R, X, and 0 perforations and that printing occurs at three different points in the machine cycle and when printing of numerals is considered, printing can be effected at four different times during the machine cycle. This is of particular advantage because of the reduction of load in the operating parts of the machine permissible over constructions where printing is effected from all the printing wheels at a single point in the machine cycle.

Selection of alphabetic characters—Lower case

In addition to printing numerals and the alphabetic type in capital letters the printing mechanism is provided with three additional groups of alphabetic characters in lower case. It will be noted from Fig. 1 that these groups correspond in character to the groups of alphabetic type in capitals. From Fig. 3 it will be noted that each capital letter has adjacent thereto a type which is the same alphabetic character but in lower case. The use of alphabetic characters in lower case is merely exemplary to illustrate one use of the improved printing arrangement. If so desired other characters may be provided and by their selection in a manner now to be explained they can be utilized for supplementary character printing.

Referring to Fig. 1 it will be noted that for the selection of a particular lower case type one of the pilot holes 0, X, R is required and in addition thereto two successive perforations at the 1-9 index point positions. For example, "l" is selected by perforations at the 9 and 8 index point positions and also at the R position. The character "f" is selected by perforations at the 6 and 5 index point position as well as the R index point position and since the previous description involved the selection of the W character the performance of the machine for selection of "w" will now be explained. When the 6 perforation is first encountered the clutch pawl 14 is unlatched in the manner previously described, this being effected by the energization of the print control magnet 75 at the 6 index point position. This will initiate the counterclockwise rotation of the disk 82 and when the successive index point position, namely "5" is correlated with the analyzing brush the selector disk 82 has been rotated sufficiently counterclockwise so that an extension 165 of the latch pawl 91 will be beneath an extension 166 of the clutch release arm 18. When the "5" perforation is analyzed at 81° in the machine cycle the print control magnet 75 for the order now being considered will again be energized, causing the extension 166 in cooperation with the extension 165 to rock pawl 91, thereby disengaging its hooked portion from the extension 167 of the arcuate plate 90. This plate will now be moved by its connected spring 92 to a position limited by the guide studs 88. Therefore, a relative movement is effected between the disk 82 and the arcuate plate 90 which has the effect of causing the cam portion 93 to be effective to rock the latch arm 62 later in the machine cycle than it would be had it not been unlatched. Therefore, in the example for selecting "w", the latch arm 62 will not be tripped at 227 $\frac{3}{4}$ ° as previously explained but at 231 $\frac{1}{2}$ ° and at this time the clutch pawl 59 will engage the notch 58 designated 6/5 which will select "w" on the printing wheel 40.

The operation of the machine as far as the control by the 0 perforation is concerned is precisely the same but it will be observed that in the case now under consideration instead of the character W being selected for printing the gear 53 will not be rotated to as great an extent, this difference being equivalent to the space between successive type of the printing wheel 40, enabling the character "w" to be selected for printing. This is readily evident because in the previous example the gear 53 is rotated an extent of eleven teeth under control of the 6 perforation line whereas the supplementary perforation

5 changes the control so that the gear 53 is rotated only ten teeth and this rotation will cause the selection of the character "w". The other characters in lower case are selected in substantially the same manner, it being observed that for the selection of the type j, k, l-r the X perforation is utilized, whereas for the selection of the remaining type of the alphabet, namely s, t, u to z the 0 perforation is utilized in combination with successive perforations at the numeral index point positions. It should also be observed that due to the inability of the machine to utilize the zero perforation as a pilot hole and also as one of the numeral index holes in the combination 1-0, no character can be selected by the combination 1-0, 0. This is not of importance because in the code of perforations selected all of the alphabet type, either capitals or lower case, can be selected for printing operations, eliminating the necessity of utilizing printing characters which do not conform to the usual character formation as has been found necessary in previously designed alphabetic printing mechanisms. In this respect it has been customary to utilize the character v for both u and v 25 character representation.

Address printing

The function of the "0" notch in disk 71 (Fig. 3) will now be explained. When the machine is plugged to plug socket 127 for alphabetic and numeral printing, a hole at the "0" position alone will cause printing from the "0" type. In printing a street number such as "205" the "0" perforation will transmit an impulse at 171° to print control magnet 15 to release pawl 14 and at this time the engaging end 73 of pawl 14 will rest on the circular part of clutch disk 71 between the "1" and "0" notch and will finally enter the "0" notch about 202°. This delay in clutching disk 71 to drive shaft 70 will enable a rotation of disk 82 but not of an extent sufficient to cause the cam edge 93 to strike projection 94. However, disk 82 will be rotated sufficiently to allow bell crank 131 to rock and close contacts 136 and these are closed by 225°. A second impulse is now transmitted at 225° by the "0" printing circuit previously described to the print control magnet 15 to cause the unlatching of the printing wheel 40 in this order to cause printing of the "0".

Selection of special symbols

The selection of the symbols is effected by the occurrence of the perforations in pairs 9-8, 8-7, 7-6, 1-0, without other perforations, i. e., without an R, X, 0 perforation, as shown in the code of Fig. 1.

It will be observed from Fig. 3 that such symbols are interspersed between the numeral type 1-9 on the printing wheel. It will also be recalled that the perforations 9-1 alone select the related numeral type of the numeral group. With the understanding that the presence of an adjacent perforation modifies the operation of the type selecting mechanism to select an adjacent type, it is clear that the special symbols will be selected for printing. An "8" hole alone selects the "8" type, but if a "7" hole follows the type wheel 40 will be rotated one type space less to select the "DR" symbol for printing. The same principle of operation is involved for the selection of the other symbol type.

While there have been shown and described and pointed out the fundamental novel features of the invention as applied to a single modifica-

tion, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a machine of the class described controlled by cards bearing holes appearing singly in a column, or bearing holes appearing in pairs but always as adjacent holes between which no other hole can appear, an operating means, a movable member carrying a plurality of groups of type, one group alternately arranged with respect to the other group, a clutch intermediate said member and said operating means, means for analyzing the card holes, means controlled 10 by said analyzing means upon the analysis of the first hole for determining the time of engagement of said clutch and said operating means for predetermining the extent of movement of said member to select a type of one group, and further means controlled by said analyzing means upon analysis of an adjacent hole, if it occurs, for changing the time of engagement of said clutch and said operating means for modifying the extent of movement of said member to select 15 a type of the other group.
2. In a machine of the class described, the combination of a movable member carrying a plurality of groups of type, one group being alternately arranged with respect to the other group, with type of the same character representation being adjacent to each other, an operating means, a clutch operating means, means for analyzing the card holes in the order 9-0, a clutch intermediate said operating means and said clutch operating means, a supplemental clutch intermediate said operating means and said member, means controlled by said analyzing means 20 upon the analysis of the first hole for engaging the first named clutch to cause the operation of said clutch operating means whereby the latter engages said supplemental clutch for predetermining the extent of movement of said member to select a type of one group, and further means responsive to the analysis of the next hole, if it occurs, for modifying the time of operation of said clutch operating means to engage said supplemental clutch whereby the extent of movement of said member is modified to select an adjacent type of the other group having the same character representation.
3. In a card controlled machine, a member carrying a plurality of type comprising one group, and a plurality of type of the second group alternately arranged with the type of the first group, means for effecting a printing impression from a selected type, means for moving said member, means for analyzing the card holes in the order 9-0, means controlled by said analyzing means for predetermining the extent of movement effected to said member by said moving means to select upon the analysis of one of the holes 9-1 alone a type of the first named group, means responsive to the analysis of a second hole adjacent the first hole analyzed with the holes appearing in combination as 9-8, 8-7 . . . 2-1, 1-0 to change the movement of the member predetermined by the first hole analyzed by the space between adjacent type to select a type of the other group, and means initiated in operation by the analysis of a supplemental hole in the card 25

utilized when either type group is selected to effect an operation of the first named means to take an impression from the selected type.

4. In a printing machine, the combination of a member carrying six groups of type, the type of one group being alternately arranged with the type of another group, means for effecting an impression from said type, means for analyzing the holes in the order 9-1, 0, X and R, type group selecting means controlled by said analyzing means for selecting in accordance with the 0, X, R holes analyzed a group of type and a group of alternately arranged type, type selecting means controlled by said analyzing means for selecting in accordance with the first hole 9-1 analyzed a type from one of the two selected groups, and further means controlled by said analyzing means in accordance with the next adjacent hole analyzed, if it appears, for controlling the operation of the type selecting means to select a type from the other of said selected groups.

5. In a printing machine the combination of a type wheel carrying six groups of type comprising three groups of alphabet capital type and three groups of lower case alphabet type, each of said capital alphabet type of each group being arranged adjacent the corresponding lower case alphabet type, means for rotating said wheel, means for effecting an impression from a selected type on said wheel, means for analyzing the holes in the order 1-9, 0, X and R, type group selecting means controlled by said analyzing means for selecting in accordance with the 0, X, R holes analyzed a group of alphabet capital type and a group of similar lower case alphabet type, type selecting means controlled by said analyzing means for selecting a desired alphabet capital type upon analysis of the 1-9 holes, and further means controlled by said analyzing means upon analyzing a hole following the first hole analyzed for controlling the operation of the type selecting means to select a lower case type for printing.

6. In a printing machine the combination of a type wheel carrying six groups of type comprising three groups of alphabet capital type and three groups of lower case alphabet type, each of said capital alphabet type of each group being arranged adjacent the corresponding lower case alphabet type, means for rotating said wheel, means for effecting an impression from a selected type on said wheel, means for analyzing the holes in the order 1-9, 0, X, and R, type group selecting means controlled by said analyzing means for selecting in accordance with the 0, X, R holes analyzed a group of alphabet capital type and a group of similar lower case alphabet type, type selecting means controlled by said analyzing means for selecting a desired alphabet capital type upon analysis of the 1-9 holes, further means controlled by said analyzing means upon analyzing a hole following the first hole analyzed for controlling the operation of the type selecting means to select a lower case type for printing, and means controlled by said analyzing means to cause the operation of said impression effecting means at different times in the operation of the machine determined by the analysis of the 0, X, R holes to print from the desired type.

7. In a printing machine the combination of a type wheel carrying seven groups of type comprising, a group of numeral type, three groups of alphabet capital type and three groups of lower case alphabet type, each of said capital alphabet type of each group being arranged ad-

jacent the corresponding lower case alphabet type, means for rotating said wheel, means for effecting an impression from a selected type on said wheel, means for analyzing the holes in the order 1-9, 0, X and R, type group selecting means controlled by said analyzing means for selecting by predetermined extents of rotation of said wheel and in accordance with the 0, X, R holes analyzed a group of alphabet capital type and a group of similar lower case alphabet type, type selecting means controlled by said analyzing means for selecting a desired alphabet capital type of a selected group upon analysis of the 1-9 holes, and a corresponding numeral type, further means controlled by said analyzing means upon analyzing a hole adjacent the first hole analyzed for controlling the operation of the type selecting means to select a lower case type for printing, means controlled by said analyzing means for effecting the operation of said impression means at different times in the machine operation in accordance with the 0, X, R holes analyzed, and means, separate from the last named means, for causing in the absence of said 0, X, R holes an impression from the selected numeral type.

8. In a record controlled printing machine which is controlled by cards bearing holes at 9-1, 0, X, R positions, a member carrying a plurality of interspersed groups of alphabet type, an electromagnet, means for effecting printing impressions from said type, means for analyzing a record to effect a double energization of said magnet when a hole 9-1 appears alone together with an 0, X, R hole, and a triple energization of said magnet when an 0, X, R hole appears with a pair of adjacent holes 9-1 such as 9-8, 8-7, 7-6, etc., means for moving said member, means controlled by said analyzing means for causing said moving means in response to the first energization of said electromagnet to initiate the movement of said member to select a type of a selected group, and in response to the analysis of a second hole of the group 9-1 to select an adjacent type of an interspersed group, if such second hole appears, means for effecting an operative connection between said electromagnet and said impression effecting means after the analysis of the 9-1 holes, and means operative in response to the second or third energization of the electromagnet by the analysis of the 0, X or R hole for causing the operation of the impression effecting means when the selected type of the selected group is at the printing point.

9. In a record controlled printing machine which is controlled by cards bearing holes at 9-1, 0, X, R positions, a member carrying a group of numeral type, and a plurality of interspersed groups of alphabet type, an electromagnet, means for effecting printing impressions from said type, means for analyzing a record to effect a double energization of said magnet when a hole 9-1 appears alone together with an 0, X, R hole, and a triple energization of said magnet when an 0, X, R hole appears with a pair of adjacent holes 9-1 such as 9-8, 8-7, 7-6, etc., means for moving said member, means controlled by said analyzing means for causing said moving means in response to the first energization of said electromagnet to initiate the movement of said member to select a numeral type, or a type of a selected alphabet group, and in response to the analysis of a second hole of the group 9-1 to select an adjacent alphabet type of an interspersed group, if such second hole ap-

pears, means for effecting an operative connection between said electromagnet and said impression effecting means after analyzing the 9—1 holes, means operative in response to the second or third energization of the electromagnet by the analysis of the 0, X or R hole for the operation of the impression effecting means when the selected type of the selected alphabet

group is at the printing point, and means separate from the last named means and effective in the absence of an 0, X, R hole or a second hole in the group 9—1 to energize said electromagnet a second time to cause the operation of the impression effecting means to print from a selected numeral type.
